FLOOR CLEANING AND POLISHING DEVICE

Emeline K. Jilbert, Blasdell, N. Y.

Application February 17, 1941, Serial No. 379,176

4 Claims. (Cl. 91—25)

This invention relates to a device for cleaning and polishing floors and more particularly to a device of this character having an applicator such as a brush, mop, or the like for applying a cleaning or polishing liquid to a floor, a storage tank or reservoir which contains a supply of said liquid and a hand operated valve mechanism which controls the delivery of said liquid from the tank to the floor and applicator.

It is the purpose of this invention to provide an improved valve mechanism for controlling the discharge of liquid from the storage tank or reservoir and simple and efficient means for detachably connecting the holder of a brush or other applicator to the handle of the apparatus.

In the accompanying drawing:

Fig. 1 is a perspective view of an apparatus embodying a satisfactory form of this invention.

Fig. 2 is a fragmentary vertical longitudinal section, on an enlarged scale, of the valve mechanism and the holder coupling of said apparatus.

Fig. 3 is a similar view of the upper part of the liquid containing tank or reservoir and the adjacent parts of the valve mechanism.

Fig. 4 is a view similar to Fig. 2 but showing the valve in a different position.

Fig. 5 is a longitudinal section taken on line 5—5, Fig. 2.

Fig. 6 is a cross section taken on line 6—6, Fig. 2.

Fig. 7 is a perspective view of the applicator holder.

In the following description similar reference characters indicate like parts in the several figures of the drawing.

In its general organization the apparatus comprises a tank adapted to contain a floor cleaning or polishing liquid, a holder adapted to receive an applicator whereby the liquid is spread over the floor, a valve mechanism whereby the discharge of liquid from the tank to the floor or applicator is controlled, and coupling means for detachably connecting the tank and holder.

The container or reservoir in which the liquid is stored preferably has the form of a longitudinal tube or hollow bar 10 which also forms the main handle whereby the apparatus is manipulated and which is usually arranged in a rearwardly inclined position when the apparatus is in use. The cleaning or polishing liquid is introduced into this tank at the upper or rear end thereof and when the apparatus is in use this end of the tank is closed by a cover consisting preferably of a screw plug 11. At its lower end the tank is provided with an annular valve 55

seat 12 which surrounds the lower outlet or port through which the liquid is discharged from the tank. Opening and closing of this port is effected by a valve 13 which preferably has the form of a ball or sphere one part of which is cut away to form a flat face 14. When this ball valve is in its closed position all parts of the annular valve seat are engaged by an annular area of the ball valve, as shown in Fig. 2, but when this ball valve is turned so that its flat surface 14 extends across a part of the annular valve seat 12, as shown in Fig. 4, then the outlet port of the liquid container is uncovered and liquid is permitted to be discharged downwardly from the container. 15 Various means may be employed for rocking the ball valve and opening and closing the same and also producing a tight joint between the same and the seat of the liquid container but this is preferably accomplished as follows: 20 The numeral 15 represents a helical spring which bears with its upper end against the under or rear side of the ball valve. On opposite sides of this spring are arranged two metal longitudinal arms or bars 16 the rear ends of which are connected and preferably formed integrally with a sheet metal sleeve 17 which is secured to the exterior of the lower part of the tubular liquid container, as shown in Figs. 1 and 5. Between their front and rear ends the side arms 16 are 25 provided with opposed hooks or fingers 9 which are struck out of the metal of the arms 16 and project inwardly and rearwardly into the front end of the helical spring 15 and form a support for this end of the same. By this means the ball valve is yieldingly held in engagement with its seat on the liquid tank so as to prevent leakage therefrom when the ball valve is closed and yet permits this valve to be easily rocked or turned for opening and closing the same. Rocking of the ball valve is effected by means which include an operating rock arm made up of two upright sections 18 having their lower ends provided with jaws 19 which engage with opposite sides of the ball valve, a rivet 20 connecting the upper ends of the arm sections, a tubular spacer consisting preferably of a plurality of sleeves 21 arranged on the rivet 20 and interposed between the arm sections 18 and a clamping bolt 22 connecting the sections 18 of the operating arm and drawing the jaws 19 of the same together so that the same grip the ball valve and compel the latter to turn with these rock arm sections. By these means it is possible to always swing the operating arm 18 through the same arc and still permit of adjusting the ball valve cir-

cumferentially relative to its seat so as to bring the flat spot 14 of the same into the proper location and also to change the area of contact between the periphery of the ball valve and its seat for producing a tight fit when this becomes necessary due to wear or other causes.

Rocking of the operating arm 18 is effected by means which include a longitudinally movable shifting rod 23 arranged lengthwise above the container 10 and connected with the rock arm 18 by a loop 24 at the front end of the rod 23 and received in an annular groove 25 in the central sleeve 21 of the tubular spacer, and a hand grip consisting preferably of a helical coil 26 arranged at the upper end of the shifting rod and slideable lengthwise on the adjacent part of the tubular container 10. This shifting rod is preferably guided on the tubular liquid container by means of a longitudinally split front guide tube 27 mounted on the upper side of the connecting tube 17 and having its sections connected by a screw 28 and receiving the adjacent lower part of the shifting rod 23, and a rear split guide ring 29 mounted on the rear part of the tubular container 10 and having its ends connected by a screw 30 and receiving between them the upper or rear part of the valve shifting rod, as shown in Figs. 1, 2, 3, and 4. The valve 13 is yieldingly held in its closed position by a helical spring 31 which surrounds the lower part of the shifting rod 23 and is connected at its lower end with the guide tube 27 while the upper end of this spring is connected with an S-shaped bend 32 formed on the shifting rod. Upon taking hold of the grip 26 and moving the same upwardly the globular valve 13 is turned in the direction for opening the outlet of the liquid container and permitting liquid to flow upon the floor or applicator and upon releasing this grip the spring 31 moves the shifting rod downwardly and closes the valve.

The applicator whereby the liquid is distributed over the floor for cleaning or polishing the same may be of various forms but in the drawing is shown as consisting of a brush having an upper rectangular stock 33 and bristles 34 projecting downwardly from the underside of the stock. The holder which carries said stock is preferably constructed of sheet metal to form a flat top 35 and two transverse channels 36 which are formed on the underside of the body at opposite edges thereof and adapted to receive the opposite edges of the brush stock. Coupling means are provided which are constructed in accordance with this invention and whereby the brush holder is detachably connected with the liquid tank forming the main handle of the apparatus. The coupling means are preferably constructed as follows:

The numeral 37 represents two coupling eyes which are arranged transversely in line on the upper side of the holder body and which are preferably formed by stamping the same upwardly out of the sheet body of the holder. In rear of these coupling eyes two retaining posts 38 are bent upwardly out of the stock of metal of the brush holder and provided on their opposing inner sides with retaining notches 39.

The front parts of the coupling arms 16 on the liquid tank are resilient and diverge forwardly and downwardly and provided at their front ends with coupling hooks or lugs 40 which project horizontally outward in opposite directions.

For the purpose of assembling the brush holder and tank handle 10 of the apparatus the front

parts of the coupling bars or arms 16 are sprung together sufficiently to permit of passing the hooks 40 between the coupling eyes and alining these arms with the notches 39 of the retaining posts 38 and upon now releasing these arms their resilience will cause them to spread and engage their coupling hooks 40 with the coupling eyes 37 and also engage these arms with the retaining notches 39. When thus assembled the brush holder will be reliably coupled with the handle tank 23 so that the brush holder is held against lateral movement and also against vertical swinging movement relative to the handle 18 and thus enables the apparatus to be moved efficiently and under complete control in all directions over the floor while cleaning or polishing the same.

This apparatus is not only very simple and efficient in construction but it also permits of quickly and conveniently disassembling and reassembling the parts for the inspection and cleaning and the several parts are of sturdy construction and not liable to get out of order under severe use.

I claim as my invention:

1. A floor cleaning and polishing device comprising a tank adapted to contain a liquid and provided with an outlet, a spherical valve engaging said outlet, and means for turning said valve including an arm constructed to grip said valve frictionally and permit circumferential adjustment of said valve and arm relative to each other.

2. A floor cleaning and polishing device comprising a tank adapted to contain a liquid and provided with an outlet and an annular valve seat around said outlet, a spherical valve engaging said seat and provided on its periphery with a flat face, and means for turning said valve including a rock arm having two sections which are provided at their inner ends with jaws which grasp opposite sides of the spherical surface of said valve, a tie connection between the outer ends of said arm sections, and a screw connection between the central parts of said arm sections.

3. A floor cleaning device comprising a tank adapted to contain a liquid and provided on its lower end with a valve seat, a rotatable ball shaped valve engaging said seat and having a flat area, and means for turning said valve so that its flat area is within the valve seat and the spherical surface of the valve engages all parts of the seat, thereby closing the tank and also turning the valve so that its flat area is opposite a part of the valve seat and thereby opens the tank for discharging liquid therefrom.

4. A floor cleaning device comprising a tank adapted to contain a liquid and provided on its lower end with a valve seat, a rotatable ball shaped valve engaging said seat and having a flat area, means for turning said valve so that its flat area is within the valve seat and the spherical surface of the valve engages all parts of the seat, thereby closing the tank and also turning the valve so that its flat area is opposite a part of the valve seat and thereby opens the tank for discharging liquid therefrom, a helical spring bearing at its upper end against the underside of said ball valve, and retaining arms arranged lengthwise on opposite sides of said spring and connected at their upper ends with said tank and provided at their lower ends with hooks which engage with the lower end of said spring.
